UNITED STATES PATENT OFFICE.

SAMUEL ROY BEAL, OF ADRIAN, MICHIGAN.

DESIGN FOR A PLAYING-CARD.

No. 38,954.

Specification for Design.

Patented Dec. 17, 1907.

Application filed December 10, 1906. Serial No. 347,214. Term of patent 14 years.

To all whom it may concern:

Be it known that I, SAMUEL ROY BEAL, a citizen of the United States, residing at Adrian, in the county of Lenawee and State of Michigan, have invented a new, original, and ornamental Design for a Playing-Card, of which the following is a specification, reference being had to the accompanying drawings, forming part thereof.

The drawing illustrates the playing card, showing my new design.

I claim:—

The ornamental design for a playing card, as shown.

SAMUEL ROY BEAL.

Witnesses:

S. E. THOMAS,
HENRY E. VILLEROT.
